VARIABLE PRESSURE INSULATION
PIERCING CRIMP

John B. Sola and Richard T. Krause, Chicago, Ill., assignors to Malco Manufacturing Company, Chicago, Ill., a partnership consisting of Al Just and Margaret R. Just

Filed Feb. 5, 1958, Ser. No. 713,413
 3 Claims. (Cl. 29—155.55)

The present invention relates to terminal connectors for electrical wires. More particularly, the invention relates to improved wire crimps for securing pierce-type terminals to insulated wires and to the method for forming the wire crimps.

In the pierce-type of terminal connector according to the present invention, one or more prongs or barbs are provided in the wire grip portion which pierce the insulation of the wire and make electrical contact with the conducting core when the terminal connector is crimped on the wire. Pierce-type connectors of the prior art provide crimping arms directly over the insulation piercing prongs in order to make certain that the prongs pierce the insulation and make proper electrical contact with the wire. Such connectors are subject to a number of limitations, particularly in that different terminal connector sizes are required for each different size of wire. This is because the prongs must be long enough to make the proper electrical contact with the wire, but at the same time they should not be long enough to pierce the other side of the insulation, since this would reduce the tensile strength of the wire and would provide undesirable, additional insulation breaks. Thus, heretofore it has been necessary for terminal users and dealers to carry large stocks of terminals of various sizes to accommodate a wide variety of wire sizes.

Accordingly, it is an object of the invention to provide an improved pierce-type terminal wire crimp.

Another object of the invention is to provide a pierce-type terminal in which the force required to pull the wire from the terminal is substantially equal to the ultimate strength of the wire.

A further object of the invention is to provide a pierce-type terminal in which the insulation piercing barbs are disposed between the crimping arms rather than under the crimping arms.

A still further object of the invention is to provide an improved pierce-type terminal in which the insulation piercing prongs are substantially longer than was possible in earlier pierce-type terminals.

Still another object of the invention is to provide a pierce-type terminal in which the insulation piercing barbs are disposed below a variable pressure clamping arm, the position of which is varied in accordance with the size of the wire being crimped to insure electrical contact between the barbs and the wire while preventing piercing of the opposite side of the insulation.

An important object of the invention is to provide an improved pierce-type terminal in which one size of the terminal can be utilized for crimping to a variety of sizes of wires to drastically reduce stocks of terminals which must be maintained.

Another object of the invention is to provide a method for forming a variable pressure pierce-type terminal connector for crimping a single size of terminal on a variety of sizes of wires.

A further object of the invention is to provide a method for forming an improved pierce-type crimp in which a pair of crimping arms of a terminal are firmly crimped about an insulated wire with at least one insulation piercing barb axially spaced between the crimping arms, to

2

permit the insulation between the arms to bulge to prevent the barb from piercing both sides of the insulation.

A still further object of the invention is to provide a method according to the previous object in which the amount of bulge between the crimping arms is controlled during crimping by applying a pressure determined by the size relationship between the wire and the terminal.

Other objects, features and advantages will be apparent from the foregoing detailed description, taken in conjunction with the accompanying drawings, in which:

FIGURE 1 is a perspective view of a pierce-type terminal connector in accordance with the present invention, shown crimped to a section of insulated wire;

FIGURE 2 is a perspective view of a terminal connector according to FIGURE 1 before the connector has been crimped to a wire;

FIGURE 3 is a top view of the terminal of FIGURE 2;

FIGURE 4 is a sectional view taken substantially along line 4—4 of FIGURE 1;

FIGURE 5 is a sectional view similar to FIGURE 4 but showing the same terminal crimped to a substantially larger wire;

FIGURE 6 is a sectional view of a pierce-type terminal of the prior art shown crimped to a section of proper size wire;

FIGURE 7 is a sectional view similar to FIGURE 6 but showing the same prior art terminal inadequately crimped to a wire the size of that shown in FIGURE 5;

FIGURE 8 is a perspective view similar to FIGURE 1 but illustrating a modified form of terminal connector with the center clamping arm eliminated;

FIGURE 9 is a sectional view taken substantially along line 9—9 of FIGURE 8.

The pierce-type terminal connector illustrated in FIGURES 1—5 is generally designated by the reference numeral 10. The terminal is formed of sheet metal of good electrical conductivity and includes a contact portion 12 and an integral wire grip portion 14. While the contact portion shown is of the forked type for connecting to a terminal post or the like (not shown), it should be understood that any desired type of contact portion may be employed.

The wire grip portion 14 has a ferrule-like configuration which is tightly formed about a section of an insulated electrical wire 16. The wire may be of any standard construction having electrical insulation 18 formed about a central, electrical conducting core 20, which is preferably stranded as shown.

The wire grip portion is provided with a pair of integral crimping arms 22, 22 which are axially spaced and which extend from one edge portion of a body or bight 24 of generally U-shaped cross-section. A central integral clamping arm 26 extends from the other edge portion of the bight 24 and is axially spaced between the crimping arms 22.

A pair of upstanding, integral insulation piercing prongs or barbs 28, 28 are formed from the metal of the bight 24, and it will be noted that the barbs are axially spaced between the crimping arms 22. Thus, the prongs are axially located in the area of the clamping arm 26, in the bottom of the bight. The barbs may be conventionally formed by punching them from the metal of the bight and bending them so that they extend upwardly with respect to the bottom of the bight, in a generally radial direction. The barbs are preferably pointed at their upper ends, as shown, leaving triangular cut-outs 30 in the adjacent portions of the bight.

The terminal connector 10 is crimped to a section of the insulated wire 16 by bending the crimping arms 22 and the clamping arm 26 about a portion of the wire, usually the end portion, which is disposed in the bight 24.

In FIGURE 4 a terminal connector of a given size is shown crimped to the insulated wire 16, of relatively small size, while in the illustration of FIGURE 5 the same size terminal is shown crimped to a wire 16a of considerably larger size with thicker insulation. In both cases the crimping arms 22 are crimped tightly about the wire to firmly secure the terminal to the wire. The pressure which is brought to bear is sufficient that the strength of the connection, or its "maximum pull test strength," is substantially equal to the tensile strength of the wire. This impels a portion 32 of the insulation between the crimping arms 22 not confined by the bight 24 to bulge substantially. When the terminal is crimped to a small size wire as shown in FIGURE 4, this bulge provides clearance for the upper ends of the prongs 28, which can thus be made substantially longer than would otherwise be possible. At substantially the same time that the crimping arms 22 are crimped about the wire, the clamping arm 26 is crimped about the insulation portion 32, but with controlled, predetermined pressure to insure that the barbs pierce only the lower portion of the insulation and make proper electrical contact with the core of the wire. In other words, the clamping arm is crimped with sufficient pressure to force the barbs through the lower portion of the insulation and through the core of the wire, but this pressure is not sufficient to cause the barbs to pierce the upper portion 32 of the insulation. The barbs should penetrate more than half way through the core for proper electrical contact, and it is preferable that they extend through the full diameter of the core as shown.

If the pressure brought to bear on the clamping arm 26 of FIGURE 4 were to be increased so that the clamping arm would be brought down to the level of the crimping arms 22, it is readily apparent that the oversize barbs 28 would pierce the portion 32 of the insulation of the small diameter wire 16, thus reducing the strength of the wire and causing unnecessary breaks in the insulation. However, where the terminal is crimped to the relatively large size wire 16a as shown in FIGURE 5, the clamping arm 26 is crimped with greater pressure to reduce or eliminate the bulge in the insulation, to insure that the core of the wire is pierced sufficiently by the barbs to provide good electrical contact.

In order to more graphically illustrate the effectiveness of the present invention, a typical pierce-type terminal 40 of the prior art is illustrated in FIGURES 6 and 7. This terminal may include a bight 42 having integral crimping arms 46 overlying a pair of insulation piercing barbs or prongs 44. The barbs of the prior art terminal are placed directly below the crimping arms, so that when the arms are crimped about the wire to hold the terminal thereon, the wire is forced onto the barbs at the same time, insuring that they pierce the insulation and make sufficient electrical contact with the core. In other words, then, the prior art crimping arms 46 perform a two-fold function in holding the terminal on the wire and in causing the barbs to pierce the insulation and make electrical contact. Because of this two-fold function performed by the crimping arms 46, the barbs must be directly below the crimping arms as shown.

Inasmuch as the prior art clamping arms must be crimped about the wire sufficiently tight to hold the terminal on the wire, it is not possible to reduce the pressure applied by these arms in order to accommodate longer insulation piercing prongs. Consequently, the conventional prongs must be quite short, as shown, and it follows that each terminal must be designed for clamping to a given size of wire, such as the small wire 16. If the terminal is crimped to a substantially larger size wire, such as the wire 16a, the barbs are much too short to pierce the thicker insulation and make proper electrical contact with the larger core, as clearly shown in FIGURE 7. Furthermore, it is not possible to apply a substantially larger pressure through the prior art crimp-

ing arms 46 when crimping a terminal on a large size wire, because this would crush the wire and cut the insulation.

According to the method of the present invention, a terminal blank is formed similar to that shown in FIGURE 2, having outer crimping arms 22 and a central clamping arm 26 which is adapted to overlay centrally located insulation piercing prongs. The next step is to insert a section of insulated wire in the bight of the terminal and to crimp the crimping arms tightly about the wire with sufficient pressure to insure that the pull-out strength of the wire is substantially equal to its tensile strength. The next step, which is performed at substantially the same time as the previous step, is to crimp 10 the variable pressure clamping arm 26 about the exposed portion of the insulation between the crimping arms with a predetermined pressure suited to the wire size and the terminal size, sufficient to cause the prongs to pierce the lower side of the insulation and to make 15 proper electrical contact with the core, but insufficient to cause the prongs to pierce the upper side of the insulation. It will be readily apparent that the method could be performed by hand, using hand tools, but it is preferable to utilize a suitable crimping machine with dies (not shown) properly set to perform the particular crimping 20 operation swiftly and uniformly.

It is possible to eliminate the central clamping arm 26 and instead to press directly against the exposed surface 32 of the insulation. In other words, the tool (not shown) 25 which would ordinarily crimp the clamping arm 26 can instead be brought down sufficiently to press against the exposed surface of the insulation with predetermined pressure sufficient to cause the prongs to penetrate the wire to the proper depth. Such a modified embodiment 30 of terminal is shown in FIGURES 8 and 9, and is generally designated by the reference numeral 10a. In this embodiment the bulged insulation 32 is exposed, but the height of the bulge was determined by the forming tool (not shown) when the terminal was crimped on 35 the wire. Thus, in this embodiment, a controlled size of bulge is provided by applying predetermined pressure directly against the exposed insulation, thus obtaining the same benefits explained in connection with the first embodiment.

40 The application of controlled pressure, through the clamping arm 26 or directly against the exposed insulation, prevents tearing or cutting of the insulation adjacent the crimping arms, thus permitting application of a somewhat greater crimping pressure through the crimping arms 22.

45 From the foregoing description it will be readily apparent that the present invention provides an improved pierce-type terminal and an improved method for forming the same in which a terminal of one size can be crimped to a variety of sizes of wires, having a variety of thicknesses of insulation, by controlling the pressure applied to the wire to cause the prongs to pierce the insulation and to make electrical contact. This is made possible by placing the insulation piercing prongs between the crimping 50 arms to take advantage of the tendency of the insulation to bulge, thus permitting the use of insulation piercing prongs which are considerably longer than would otherwise be possible. The provision of oversize prongs together with application of controlled pressure on the insulation over the ends of the prongs allows drastic 55 reduction in the number of sizes of terminals which must be produced and stocked, and, consequently, provides a great saving in time, material and manpower.

60 Variations and modifications may be effected without departing from the scope of the novel concepts of the present invention.

65 We claim:

70 1. A method of crimping a metallic terminal to an insulated wire in a range of sizes from a predetermined 75 minimum diameter to a predetermined maximum diam-

eter through controlling bulging of the crimped wire, comprising the steps of forming a terminal having at least one insulation piercing prong and crimping means axially spaced on each side of said prong, said prong having a length which is greater than one-half the diameter of the bare wire plus the thickness of the insulation on one side of the maximum diameter wire but is no greater than the diameter of the bare wire plus the thickness of the insulation plus the increase in thickness due to bulging of the minimum diameter wire, crimping said terminal to the wire with a relatively high pressure to secure the terminal thereon and to induce the insulation to bulge in an area opposite to said prong, and pressing said insulation in said area with a controlled pressure different from and unrelated to said high pressure to cause the prong to pierce the insulation only on the side opposite to said area and to penetrate more than half way through the core of the wire to make good electrical contact with the core.

2. A method of crimping a metallic terminal to an insulated wire in a range of sizes from a predetermined minimum diameter to a predetermined maximum diameter through controlling bulging of the crimped wire, comprising the steps of forming a terminal having at least one insulation piercing prong and a pair of crimping arms axially spaced on each side of said prong, said prong having a length which is greater than one-half the diameter of the bare wire plus the thickness of the insulation on one side of the maximum diameter wire but is no greater than the diameter of the bare wire plus the thickness of the insulation plus the increase in thickness due to bulging of the minimum diameter wire, crimping said arms about said wire to clamp the terminal to the wire with a relatively high pressure while permitting the insulation of the wire between the arms to bulge, and pressing the bulged insulation with a controlled pressure different from and unrelated to said high pressure to cause the prong to pierce the insulation only on the side opposite and to penetrate more than half way through the core of the wire to make good electrical contact with the core.

3. A method of crimping a metallic terminal to an insulated wire in a range of sizes from a predetermined minimum diameter to a predetermined maximum diameter through controlling bulging of the crimped wire, comprising the steps of forming a terminal having at least one insulation piercing prong with a pair of crimping arms axially spaced on each side of said prong and a central clamping arm between said crimping arms, said prong having a length which is greater than one-half the diameter of the bare wire plus the thickness of the insulation on one side of the maximum diameter wire but is no greater than the diameter of the bare wire plus the thickness of the insulation plus the increase in thickness due to bulging of the minimum diameter wire, crimping said crimping arms about said wire to clamp the terminal to the wire with a relatively high pressure while permitting the insulation of the wire between the crimping arms to bulge, and forming said clamping arm about the bulged insulation with a controlled pressure different from and unrelated to said high pressure to cause the prong to pierce the insulation on the side of the wire opposite to the bulged insulation only and to penetrate more than half way through the core of the wire to make good electrical contact with the core.
